UNITED STATES PATENT OFFICE.

ROBERT HAINSEY, OF ALTOONA, PENNSYLVANIA.

RAILWAY SWITCH.

1,408,503.

Specification of Letters Patent.

Patented Mar. 7, 1922.

Application filed December 9, 1919. Serial No. 343,689.

To all whom it may concern:

Be it known that I, ROBERT HAINSEY, a citizen of the United States, residing at Altoona, in the county of Blair and State of Pennsylvania, have invented certain new and useful Improvements in Railway Switches, of which the following is a specification.

This invention relates to railway switches. The object of the invention is to so construct such a switch that when it is locked in position an engine or car can run through it without tearing out the lock-keepers or bending the lever rod and which returns to its initial position after the passage of the engine or car.

Another object is to provide means whereby an engine or car is prevented from "picking the switch" when passing over it.

Another object is to provide springs for reliably holding the inside rails against the outside rails and thus preventing "picking of the switch."

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a top plan view of a switch constructed in accordance with this invention; and

Fig. 2 is a transverse section taken on the line 2-2 of Fig. 1.

In the embodiment illustrated a pair of outside rails 1 and 2 are shown, between which are located the inside rails 3 and 4. The inside, or switch rails, 3 and 4 are connected by flat bars or plates 5 and 6 which are exactly alike in construction and hence one only will be described in detail. The bar or rail 6 which connects the points of the switch is about 3" broad, more or less, and the opposite ends thereof are offset upwardly and bolted to clamping plate 7 carried by the rails 3 and 4, being preferably riveted thereto. Arranged under bar 6 and projecting at its ends beyond the ends of said bar, is a plate 8 which is secured to bar 6 and the clamping plate 7 by bolts 9 to provide for the separation of these parts when desired,

the bar 6 being riveted to plate 8 as shown at 9^a at point spaced inwardly from the connection of bar 8 in the clamping plates. This bar 8 has an offset central portion 11 forming between it and plate 6 a box-like structure, or housing, the ends of which are apertured, as shown at 10, and have bushings 12 and 13 secured to the inner faces of said ends. 65

Slidably mounted in these bushings 12 and 13 and extending through the box-like structure, above referred to, is a switch shifting rod 14 composed of two sections 15 and 16, the inner ends of which are threaded and 70 screwed into a connecting member 17. Mounted on these rod sections 15 and 16 within the box-like portion of plate 8 are two coiled springs 18 and 19 secured at their outer ends to the flanges 20 of the bushings 75 12 and 13, the inner ends of said springs engaging a flange 21 on the connector 17.

Rod section 16 extends beyond the track and is shown passed through a hanger 16^a and is designed to be connected with an actuating lever not shown. 80

Brace bars 22 connect the plate member 11 with the ends of plate 8, as is shown clearly in Fig. 2, and are apertured, as shown at 23, for the passage of the rod 14. 85

The ends of plate 8 extend beyond the main track rails 1 and 2, as is shown clearly in the drawings, and when the structure, which connects the inner rails 3 and 4, is shifted transversely to cause one of the 90 switch rails to engage either the track rail 1 or 2 according to the direction it is designed to direct the car to pass thereover one of the springs is put under compression so that when the rod 14 is released this 95 spring will operate to return the switch rails 3 and 4 to normal position, leaving the main track open.

These springs 18 and 19 are also designed to normally hold the switch rail securely in 100 contact with the main track rail, as shown at the right of Fig. 2, so that all danger of a car or engine "picking the switch" is avoided.

Having thus fully described my invention, 105 what I claim as new and desire to secure by Letters Patent, is:

1. In a switch of the class described, a pair of outer rails and a pair of inner rails, a bar connecting said inner rails, a second 110 bar secured to the first bar and extending beneath the outer rails, a box-like structure

formed on the second bar intermediate its ends, a rod slidable through the ends of said box-like structure and adapted to be connected to a switch lever, said rods being in 5 sections, a coupling detachably connecting said sections, a stop carried by the coupling, coil springs on said rod sections bearing at one end against said stop and at their outer ends against the ends of the box-like 10 structure.

2. In a switch of the class described, a pair of outer rails, and a pair of inner rails, a clamp situated on the inner face of the inner rails, a bar connecting said clamps, a 15 second bar secured to the first bar and to the clamp and extending beneath the outer rails, a box-like structure formed on the second bar intermediate its ends, a rod slid- 20 able through the end of said box-like struc- ture and adapted to be connected to a switch lever, said rod being in sections, a coupling detachably connecting said sections, a stop carried by the coupling, coil springs on 25 said rod sections bearing at one end against said stop and at their other ends against the ends of the box-like structure.

3. In a switch of the class described, a pair of outer rails and a pair of inner rails, a bar connecting said inner rails, a second 30 bar secured to the first bar and extending beneath the outer rails, a box-like structure formed on the second bar intermediate its ends, a rod slidable through the ends of said box-like structure and adapted to be con-

nected to a switch lever, said rod being in 35 sections, a coupling detachably connecting said sections, a stop carried on the coupling, coil springs on said rod sections bearing at one end against said stop and at their outer ends against the ends of the box-like 40 structure, and braces connecting the ends of the second mentioned bar with the box-like structure.

4. In a switch of the class described, a pair of outer rails and a pair of inner rails, 45 a clamp provided on the inner face of each inner rail, a bar connecting said clamps, a second bar secured to the first bar and to the clamps, and extending beneath the outer rails, a box-like structure formed on the sec- 50 ond bar intermediate its ends, a rod slidable through the ends of said box-like structure and adapted to be connected to a switch lever, said rod being in sections, a coupling detach- 55 ably connecting said sections, a stop carried by the coupling, coil springs on said rod sections bearing at one end against said stop and at their other ends against the ends of the box-like structure, and braces secured to the ends of the second bar and 60 to its box-like structure.

In testimony whereof I affixed my signature in presence of two witnesses.

ROBERT HAINSEY.
